UNITED STATES PATENT OFFICE.

GEORGE C. BECK, OF SPOKANE, WASHINGTON.

AUTOMOBILE-BRAKE.

1,315,699.

Specification of Letters Patent. Patented Sept. 9, 1919.

Application filed June 24, 1918. Serial No. 241,605.

To all whom it may concern:

Be it known that I, GEORGE C. BECK, a citizen of the United States of America, residing at Spokane, in the county of Spokane 5 and State of Washington, have invented new and useful Improvements in Automobile-Brakes, of which the following is a specification.

This invention pertains to automobiles 10 and has for its object to provide an improvement in brakes and has particular application to automobiles where the brake-bands operate over a drum inclosed within the transmission housing, as on a Ford construction.

It is often that brake bands have to be removed for the purpose of relining and for other purposes. In order to remove and to replace the brake-band, as generally constructed, it is necessary to remove at least 20 the upper portion of the housing. By my improved construction of brake-band, the same can be removed and replaced through the normal opening in the transmission 25 housing without removing any portion of the housing. I accomplish my purpose by providing a specially constructed removable ear to the brake-band and attaching a leader to the brake-band and temporarily securing same to the drum, then rotating the drum, drawing the brake-band around the drum within the housing, the end of the brake-band having the ear removed being free to pass between the drum and the housing. 30 The brake-band can be removed and replaced in this manner. In the accompanying drawings forming a part of this specification,

Figure 1, is an end view of the brake-drum, showing the brake-bands attached thereto, and a sectional view of the housing.

Fig. 2, is a side view of the same without the housing.

Fig. 3, is a side view of the improved 45 brake-band with the leader attached thereto.

Fig. 4, is an edge view of the same.

Fig. 5, is a broken-away view of one end 50 of the brake-band with the ear attached thereto, and one form of leader attached.

Fig. 6, is a detail view of the leader detached.

Fig. 7, is a longitudinal sectional view of Fig. 5, with the parts partially separated to show manner of assembling.

Fig. 8, is a plan view of another form of leader.

Fig. 9, is a perspective broken-away view of one end of the brake-band with the ear partially attached thereto and showing the manner of assembling the two parts together.

Fig. 10, is a longitudinal sectional view of one end of the brake-band with the ear and form of leader shown in Fig. 8 attached thereto, and

Fig. 11, is a broken-away view of Fig. 10 somewhat enlarged and with the parts partially separated to show the manner of assembling.

In the class of automobiles mentioned, the 70 brake-drum 10 is in close proximity to the housing 11, there being only a narrow space 12 between the two. The brake-bands 13 encircle the drum 10 within the space 12. The brake-rods for controlling the brake-bands 13 pass through openings in ears 15 attached to the ends of the brake-bands 13. When it is necessary to remove the brake-bands 13 from their positions as shown in Fig. 1, for the purpose of relining or for 80 other purposes, as is frequently the case, heretofore it has been necessary to remove the upper portion 11^a of the housing 11, as it was not convenient to remove and replace the brake-band 13 otherwise. I have made 85 one of the ears 15 conveniently removable and replaceable by the construction shown in the drawings and hereinafter described so that I am able to remove and replace the brake-band without removing the portion 90 11^a of the housing 11. The ear 15 is made removable and replaceable by providing an open slot 27 in the lower end of the ear 15 and placing on the brake-bands 13 a stud 16 over which the ear 15 may be secured by 95 reason of the slot 27. The ends of the brake-band 13 are curled up as at 17 and a projection 18 at the front end of the ear 14 is adapted to engage the space 19 between the body of the brake-bands 13 and the curled 100 portion 17. A stud 20 on the outer surface of the brake bands 13 resting in an opening 21 in the ear 15 serves to steady and hold the brake-bands 13 and the ear 15 in rigid relation to each other. A slot 22 on 105 the curled over portion 17 is provided whereby a lever 23 may be attached thereto, the portion 24 engaging the opening 19 in the brake-band 13, the portion 23^a extending through the slot 22 and the pin portion 25 110 26 adapted for engagement in an opening 26 provided in the brake-drum 10.

When it is desired to remove a brake-band 13 it is only necessary to remove the brake-rod 14 and the removable ear 15 and then draw the brake-band 13 by the other ear 5 out of the housing 11 through the small normal opening 28. When it is desired to replace the brake-band 13 upon the drum 10, the leader 23 is placed in the brake-band 13 as shown in Fig. 7, the ear 15 being removed, the pin portion 25 inserted in the opening 26 in the drum 10 and the drum 10 rotated once around. This carries the brake-band back to place over the drum 10. The leader 23 is then removed and the ear 15 placed in position by inserting the slot 27 over the stud 16, then clamping the extension 18 into the opening 19 underneath the curled over portion 17, the stud 20 falling into the opening 21. The brake-rod 14 can 20 then be replaced.

Another and preferred form of construction is shown in Figs. 8, 10 and 11, whereby a disk leader 29 is secured to the brake-band 13 by means of a pin or rivet 30, extending 25 through the opening 31. In the opposite end of the disk leader 29 is a pin 32, the end of the disk leader being bent over as at 33 to retain the pin 32. The brake-band 13 is carried around the drum 10 in the same manner as in the formerly described construction, the pin 32 engaging the opening 26 in the drum 10 and the ear 15 replaced by inserting the slot 34 over the stud 35 and making the ear 15 rigid with the brake-band 13 by means of a stud 36 threaded into a bearing 37 riveted to the brake-band 13, the stud 36 extending through the ear 15.

What is claimed is:

1. In automobiles, an improvement in

brakes, comprising in combination a brake- 40 drum formed with an opening therein, a brake-band engageable with the brake-drum, separated and having two ends, a removable ear on one of the ends and a leader attached to the end to which the removable ear is af- 45 fixed and insertable into the opening on the brake-drum.

2. In automobiles, an improvement in brakes comprising in combination a brake-drum, means for attaching a leader thereto, 50 a brake-band engageable with the brake-drum, separated and having two ends, a removable ear on one of the ends, a leader attached to the end of the brake-band from which the ear is removed, and means for replacing the ear on the brake-band which comprises a stud and slot engagement of the ear and brake-band at one end of the ear and a threaded stud connection near the other end of the ear. 60

3. In automobiles, an improvement in brakes comprising in combination, a brake-drum formed with an opening therein, a brake-band separated, and having two ends, engageable with the brake-drum, and having 65 two ears attached to the separated ends thereof and operating devices in connection with the ears, one of the ears being removable from the brake-band and a leader attachable to one end of the strap and having 70 an end formed to fit into the opening in the drum.

In testimony whereof, I affix my signature in presence of two witnesses.

GEORGE C. BECK.
